UNITED STATES PATENT OFFICE.

WALTER A. KNIGHT, OF MADISONVILLE, OHIO, ASSIGNOR TO FEDERAL CANNING MACHINERY COMPANY, OF INDIANAPOLIS, INDIANA, A CORPORATION OF INDIANA.

FILLER.

No. 925,109.

Specification of Letters Patent.

Patented June 15, 1909.

Application filed June 28, 1906, Serial No. 323,869. Renewed April 22, 1909. Serial No. 491,600.

To all whom it may concern:

Be it known that I, WALTER A. KNIGHT, a citizen of the United States, residing at Madisonville, in the county of Hamilton and 5 State of Ohio, have invented new and useful Improvements in Fillers, of which the following is a specification.

My invention relates to machines for filling fruit or other goods to be preserved by canning into containers, said filling machines of the type disclosed in the application of Charles F. Gray, of Indianapolis, Indiana, filed May 25th, 1906, Serial Number 318,718, employing means for exhausting the air from 15 the container, so that air pressure on a superimposed body of goods in the hopper will force the goods into the container, completely filling it.

It is found advantageous to be able to handle a plurality of sizes of containers on a single machine, and my improvements provide means of adjustment to that end.

My invention is illustrated in the accompanying drawings, in which:—

25 Figure 1, is a side elevation of the Gray filler, showing means of adjustment of the bed length, length of levers, position of container's chute, and length of knife rod. Fig. 2, is a detail of the vacuum chest, its valve 30 and controlling mechanism, with the interfering parts of the bed broken away and the vacuum chest in section. Fig. 3, is a crank shaft formed with an adjustable wrist-pin. Fig. 4, is a detail of the modified crank. Fig. 35 5, is a vertical lateral section through the bed and false sides permitting adjustment to containers of different size diameters. Fig. 6, is an enlarged detail of a portion of the bed with the chute plate and attendant parts and 40 means for altering the length of the bed. Fig. 7, is a vertical lateral section through the levers where they telescope for adjustment. Fig. 8, is an enlarged detail of the knife rod adjusting mechanism.

45 Referring now to the drawings, F, is the frame with journals, f, f, thereon.

C, is the bed, whose bottom is slotted at the rear by slot, c. A, the driven shaft, with pulley, a, and pinion, a¹, rotatively attached thereto; B, the crank shaft, with gear, b, and cams, b², and b³, rotatively attached thereto; E, the vacuum chest whose bottom, E¹, has nozzle, e¹³, surrounding exit opening, e¹¹, and

surrounded by air holes, e¹², these in turn surrounded on under side by compressible 55 packing ring, e, knife e⁶, slidably adjustable longitudinally within the chest, E, next the bottom with perforations, e⁷, adapted to register with e¹¹, and perforations, e⁸, adapted to register with those, e¹², said knife actuated 60 from without through compound rod e⁵, e⁴, e³, e², the latter piercing bracket, e¹; lever, G, pivoted to the bed at c¹, plunger rod, g, guided by support, g², and carrying plunger g¹, said plunger fixed at a predetermined 65 height, by nuts, g⁴, g⁵, and weight, g³, adapted to normally depress lever, G, together constituting the container elevating mechanism; I, the hopper extending through the vacuum chest and terminating at the knife 70 in an opening, i, adapted to register with perforation, e⁷; J, the container chute; H, the container forwarder, with its tee head, h¹ preferably integral therewith and connecting rod, h, journaled thereto; D, the air tank 75 connected to the vacuum chest through the pipe, d², rocker valve, d, and pipe, d¹, and to the steam pipe, d⁴, through the pipe, d³, check valve, d¹⁰, and ejector, d⁹, and the lever, d⁵, pivoted to the bed at c², and to the 80 lever, d⁶, which in turn is pivoted to the valve lever, d⁷, the weight, d⁸, adapted to normally hold the forward end of the lever, d⁵, depressed, together constituting the valve operating mechanism; all said mechanism together constituting said Gray's invention, which it is necessary to review to point out the nature and operation of my improvements.

The width of the bed may be adapted to 90 various sizes of containers by securing false sides, C¹, to the inner surfaces of the sides of the bed. This may be done in any desired manner as with screws, c³, whose heads, c⁴, are adapted to rotate freely in longitudinal 95 recesses, c⁵, milled in the false sides, C¹, said screws, c³, being threaded through the sides, C, making the false sides, C¹, adjustable toward and from each other to form a passage between them of suitable width for the 100 particular size container to be filled.

The length of the bed between the container chute, J, and the chest opening, e¹¹, is made adjustable in any convenient way; as by forming said bed of a forward and rear 105 section, said sections dove-tailed together;

the inserting strips on the forward portion are designated as, c^6 , and those on the rear portion as c^7 . Longitudinal movement is secured and the desired position maintained 5 by rotating any suitable number of bolts, c^8 , with right and left threads, operating through lugs, c^9 , in pairs, one on the rear and the other on the forward portion of the bed. Lock nuts, c^{10} , may be provided for more 10 securely maintaining the desired position of the bolt.

The container chute, J , terminates at its lower end in a plate, j , which has a flange, j^1 , corresponding to a flange, c^{11} , on the outer 15 side of the upper edge of the bed. Bolts, j^2 , pierce the flange, j^1 , and the flange, c^{11} , the latter being slotted to permit of longitudinal adjustment of the container chute plate, j . The chute, J , is usually a sheet metal pipe 20 and sizes adapted to fit different diameter cans may be provided. Provisions for fitting such sizes may be made at the plate, j , in the form of suitable bushings, j^3 , whose lower outer diameter fits the perforation of 25 the plate and whose inner diameter fits a smaller sized chute. Longitudinal adjustment of the plate, j , as provided above, permits delivery of any size of containers just in front of the forward face of the plunger, H .

30 Adjustment of the stroke of the sliding head, so as to be equal to the diameter of any particular sized containers, is provided by making the wrist pin, b^1 , adjustable. The following is a simple and convenient way.

35 The wrist-pin is composed of the bolt, b^4 , which pierces the sides, b^5 , of the crank and cylindrical surrounding sleeve, b^6 , which is the same length as the normal width of the crank. Bolt, b^4 , is provided with one or 40 more nuts, b^7 , on each end, or may have a fixed head on one end. The crank sides, b^5 , have slots, b^8 (see Fig. 4), adapted to receive the bolt, b^4 , and admit of its adjustment therein to secure the desired stroke.

45 Lever, d^1 , is made somewhat adjustable as to length in any convenient way as by telescoping and retaining with a screw, d^{11} , (see Fig. 7). Lever, G , is made likewise adjustable and held with a screw, g^6 .

50 Provision is made for several points, c^1 , where lever, G , may be pivoted to the bed, C ; and provision is made for several points, c^2 , where lever, d^5 , may be pivoted to the bed, C .

55 The upper part of the sliding head, H , is made of such a width as to reciprocate in the bed, C , when the smallest diameter containers are to be filled; and its width is increased for containers of greater diameter 60 by adding plates, h^2 , of suitable and equal thickness to its sides. These may be held in any convenient way as by screws, h^3 . There must also be a plurality of plates, E^1 , and knives e^6 , with corresponding perfora-

tions adapted to the container apertures of 65 the several sizes of containers to be filled.

The knife, rod e^5 , is made somewhat adjustable as to length in any convenient way as by telescoping in a sleeve, e^{14} , and fixing in position with a screw, e^{15} (see Fig. 8). 70

My improvements are utilized as follows: Let us presume that the machine has been used on some large containers as on ordinary tin tomato cans and it is now desired to fill corn cans, which are not so high and of 75 much smaller diameter.

(1) Narrow the sliding head, H , by removing from each side one or more plates, h^2 , or replacing with thinner ones, so that the width of the head is approximately equal to 80 the diameter of the corn can.

(2) Adjust the false sides, C^1 , by means of the screws, c^3 , so that they are closer together, and form a passage in the center of the trough of the bed sufficiently wide to 85 allow the corn can to be pushed along the bed lengthwise without binding.

(3) Adjust the sleeve, b^6 , and the bolt, b^4 , so as to produce a stroke of the sliding head theoretically equal to the diameter of the 90 corn can, but in actual practice a little more, so as to leave a slight clearance under the can chute, J , that the cans may not fail to drop to the floor of the bed.

(4) A bottom, E^1 , and a knife, e^6 , having 95 goods and air apertures adapted to the opening of the corn can, will replace those now on the machine for tomato cans.

(5) Loosen the screws, e^{15} , d^{11} , and g^6 , and the nuts c^{10} . Revolve the bolts, c^8 , lengthening or shortening the bed as is most expedient, until the sliding head when at the extreme limit of its forward stroke acts upon any number of the corn cans, so as to exactly center one of said cans over the plunger, g^1 , and under the exit opening, e^1 . Then tighten down the nuts, c^{10} .

(6) The levers, G , and d^5 , and the rod, e^5 , have been lengthened or shortened as the case may be, by the adjustment of the 110 length of the bed, so tighten down the screws, g^6 , d^{11} , and e^{15} .

(7) Adjust the plunger rod, g , by means of nuts, g^4 , g^5 and change the pivot to any of the points, c^1 , to secure the proper stroke of 115 the plunger, g^1 , through the lever, G , when actuated by the cam, b^2 .

(8) Change the pivot to any of the points, c^2 to secure the proper stroke of the lever, d^7 , of the valve, d , through the lever, d^5 , 120 when actuated by the cam, b^2 .

(9) Adjust the position of the plates, j , of the can chute, J , by moving the bolts, j^2 , so that the cans will fall just in front of the face of the sliding head, when at its extreme 125 rearward position; place the proper size bushing, j^3 , in position and put suitable size chute, J , in place.

It will be apparent that the steam pipe, d^4 , must have a flexible connection (not shown).

All the adjustments are now made and the machine is ready to be operated as described in the application of Gray.

I claim as my invention and desire to secure by Letters Patent of the United States:—

- 10 1. In a machine of the character described, the combination of a bed, a head slidably mounted therein, supplemental or false sides with said bed, and means for adjusting the false sides toward and from each other to 15 vary the transverse diameter of the bed.
2. In a machine of the character described, the combination of a bed having permanent sides, false sides removably mounted between said permanent sides, and means carried by the permanent sides and engaging said false sides to move the latter toward and from each other to adjust the internal transverse diameter of the bed.
3. In a machine of the character described, the combination of a bed, a head slidable therein, and means for adjusting the throw of the head, said means including a shaft, crank arms rigid therewith, and a crank pin adjustable radially of the shaft.
- 30 4. In a machine of the character described, the combination of a bed, a head operable

therein, and means for operating the head, said bed formed of sections adjustable longitudinally one relative to the other.

5. In a machine of the character described, 35 the combination of a two-part bed, a head operable therein, means for operating the head, and adjusting screws turnably mounted on one part of the bed and engaging nuts on the other part of said bed, for adjusting 40 the length of the bed.

6. In a machine of the character described, the combination with the bed, a head slideable therein, means for operating the head, means for adjusting the length of the bed, 45 means for adjusting the width of the bed relative to said head, a filling hopper beneath which containers are fed by the head, a plunger for elevating the container into operative engagement with the hopper, an 50 operating power shaft, and connections between said shaft and plunger said connections being adjustable as to length and fulcrum.

In testimony whereof I have hereunto set 55 my hand in presence of two subscribing witnesses.

WALTER A. KNIGHT.
